UNITED STATES PATENT OFFICE.

JULIAN R. HARRISON, OF BARNWELL, SOUTH CAROLINA, ASSIGNOR TO
FOUNTAIN COMB & NOVELTY COMPANY, OF NEW YORK, N. Y., A
CORPORATION OF NEW YORK.

FOUNTAIN-COMB:

SPECIFICATION forming part of Letters Patent No. 734,704, dated July 28, 1903.

Application filed December 3, 1902. Serial No. 133,692. (No model.)

To all whom it may concern:

Be it known that I, JULIAN R. HARRISON, a citizen of the United States, residing in Barnwell, in the county of Barnwell and State of 5 South Carolina, have invented certain new and useful Improvements in Fountain-Combs, of which the following is such a full, clear, and exact description as will enable any one skilled in the art to which it appertains to 10 make and use the same, reference being had to the accompanying drawings, forming part of this specification.

My invention relates to what is known as a "fountain-comb," and in which the teeth 15 are made hollow or tubular and are in communication with a suitable reservoir in the body of the comb and are each provided with a valve which is opened when the end of the tooth is pressed in contact with the scalp for 20 the purpose of treating the scalp with fluid preparation. The principal objects of the present invention are to provide a fountain-comb of this class in which the valve of each tooth is rendered quite sensitive and easy of 25 operation and the tension on which may be readily adjusted and to guard against leakage of the liquid from the comb when the same is not in use.

With these and other objects in view my 30 invention consists in the various novel and peculiar arrangements and combinations of the several parts of the device, all as herein-after fully described and then pointed out in the claims.

35 I have illustrated types of my invention in the accompanying drawings, wherein—

Figure 1 is a perspective view of a fountain-comb embodying my improvements. Fig. 2 is an enlarged central vertical sectional view of a portion of the fountain-comb shown in Fig. 1. Fig. 3 is an enlarged section on a central vertical plane through the comb, showing a modified form of the invention. Fig. 4 is a vertical central section of a modified form of the comb. Fig. 5 is a similar view of another modification.

Referring to the drawings, in which like numbers of reference designate like parts throughout, 1 is the body of the comb, which

is cylindrical and formed with a liquid-tight 50 chamber 2, which constitutes the reservoir for holding the liquid with which the comb is charged. From one end of the body of the comb extends in line therewith a handle 3, which is flattened in a vertical direction—that 55 is, in the plane in which the teeth of the comb are contained. The other end of the comb-body is open and is provided with a removable plug 4, which fits into the end of the reservoir and forms a liquid-tight joint therewith. The joint between the plug 4 and the mouth 5 of the reservoir is shown as formed without screw-threads, it being a smooth tapering joint, and the reservoir is charged with liquid by removing the cap 4 when desired. 60

Upon the under side of the comb-body 1 is arranged a row of hollow or tubular teeth 6, which are in direct communication with the interior of the reservoir and are open at their lower ends or points in order that at a certain time the liquid contents of the reservoir may pass therefrom through the tooth and out of the point thereof. I refer to these teeth as being "tubular," and by that I mean that they are pipe-like structures, which may assume any shape in cross-section, either interiorly or exteriorly, and more or less of these teeth are used, depending upon the size of the comb. The bore of the tooth of the comb is practically unobstructed in its communication with the reservoir, and upon its lower end upon the interior there is formed a conically-shaped valve-seat 7, with which cooperates a valve 8, conically-shaped. This conical valve 8 has extending from its apex 85 or lower end an outer valve-stem 9, which extends through the mouth 10 at the end of the tooth and projects out beyond the same, while the upper end of the valve carries an inner stem 11, which is made sufficiently long to 90 reach into the reservoir 2 in order that it may have the additional function of leading the liquid from the reservoir down through the interior of the tooth to the lower end thereof, from where it is discharged. The upper part 95 of the valve 8 is formed with a cylindrical part 12, around which fits the lower end of a spiral spring 13, which surrounds the upper

valve-stem 11 and has its upper end resting against a fixed part in order to keep the valve on its seat with spring-pressure.

In the construction shown in Fig. 2 the tubular or hollow teeth 6 are each made integral with the body 1 of the comb for the purpose of simplifying the construction and avoiding a joint between each tooth and the comb-body. In this construction the upper valve-stem 11 extends through the reservoir to a point in the opposite wall thereof, where there is formed a perforation 14, into which fits an adjustable cap 15, having the exterior thereof tapering downwardly, so as to be fitted tightly within the opening 14. This cap 15 is hollowed out at 16 on its inner end, so as to receive the upper end of the spring 13 therein, and it has in the bottom of the hollow a smaller recess 17, into which the head 20 of the upper valve-stem 11 loosely projects and by which it is guided. The tension on the spring 13 may be varied by vertical adjustment of the cap 15 in its opening in the side of the reservoir, the tension being greater 25 the farther the cap is forced down in its seat. In Fig. 2 the valve of the tooth at the extreme left hand is shown as closed, and this is its normal position in order that the fluid 18 may not escape from the tooth. The tooth 30 next adjacent is shown with its valve pressed inwardly and open, which is the position it assumes when the comb is pressed against the scalp and the outer valve-stem 9 is pushed within the tooth. These two valves are shown 35 in these positions in order to illustrate each position of the same, it being understood that in the use of the comb the valve of each tooth is opened by the outer stem thereof being pressed down against the scalp, and this may 40 occur with all of the teeth simultaneously or not, depending, of course, which of the teeth come in contact with the scalp. In this construction of the invention the hollow teeth 6 and the comb-body 1 being integral they may 45 be cast or molded at one operation, likewise the conical seats 14 for the adjustable plugs 15. After thus molding these parts the conical valve-seat 7 in the respective teeth may 50 be drilled and made true by inserting a drill through the opening 14 in the side of the body and down into the tooth opposite such opening. After this is done the valve, with 55 its spring, is set in place with the lower stem 9 extending down through the end of the tooth and the plug 15 being put in place over the end of the upper stem 11 and forced down in its seat.

In the construction shown in Fig. 3 the tooth 6 is set through an opening 19 in the side of the reservoir and is formed with an inner extension 20, which extends across the reservoir through an opening 21 therein at a point opposite the opening 19 and projects beyond the outer side of the reservoir, where 65 it is formed with an external screw-thread 22, upon which fits an internal screw-threaded

cap 23. The tooth 6 is formed with an external annular flange 24, which rests against the outer side of the reservoir around the opening 19, and when the cap 23 is screwed 70 upon the upper end of the extension 24 against the exterior of the body 1 it brings the cap 23 down against the exterior of the body 1, making a liquid-tight joint at both of these points. In order, however, to prevent leakage at these points, a soft washer may be interposed at both places. In this form the valve is the same as described in reference to Fig. 1, and the upper valve-stem 11 is guided in an opening 25, formed in a cross-piece 26, arranged in the upper end of the extension 20, and the upper end of the spring 13 bears against this cross-piece 26, which is fitted snugly within the exterior of the tubular extension 20, so that it may be forced up 80 or down therein in order to vary the tension on the spring. At suitable points in the sides of the extension 20 are perforations 27, through which the liquid 18 may pass from the reservoir down into the bore of the tooth 90 6. In this form of the construction the interior of the tooth 6 is practically in direct communication with the interior of the reservoir.

In the construction shown in Fig. 4 one of 95 the teeth 6 has its inner end threaded at 28 and screwed into a threaded opening 29 in the side of the reservoir, and it is formed with an annular flange 30, which rests against the outer surface of the body or barrel 1. The opening 29 is reduced at 31, where it communicates with the reservoir, in order to provide a fixed part against which the spring 13 of the valve may rest at its upper end. The upper stem 11 of the valve projects into 100 the reservoir 2, and the interior of the tooth 6 is in direct communication with the reservoir, as in the other constructions.

In Fig. 4 the tooth at the right-hand side of the figure is shown as being without any 110 screw-thread and is inserted tightly within the opening 29, a screw-thread being thus avoided.

The reservoir 2 may be provided with a suitable air-inlet 32, which in Fig. 4 is shown 115 as of a comparatively smaller size in order to let the air enter the reservoir above the liquid and assist the discharge of the liquid from the points of the teeth of the comb when the valves are pressed in. In cases 120 where the air-inlet is dispensed with the discharge of the liquid from the points of the teeth will depend upon capillary action in a manner well known, and this may be sufficient in some cases for the purposes for which 125 the fountain-comb is used.

It will be noted that in each of the forms of the invention herein shown the bore of the tooth of the comb is normally filled with liquid from the reservoir down to the point where 130 the valve 8 is located, so that as this valve opens the liquid at once finds its way to the

point of the tooth, and it flows from the same to the point of application, some of the liquid also finding its way down the end of the stem 9. The flow of liquid from the point of the tooth may be made more or less copious by increasing or diminishing the space between the mouth of the opening at the end of the tooth and the valve-stem 9, which projects through the same, by enlarging or reducing the diameter of either the stem or the interior of the tooth at the end. Of course the number of tubular teeth may be increased as desired, and the cross-sectional area of the tooth may be made as small as practical in order to offer less resistance to the movement of the comb through the hair. In making this article any well-known and suitable material, such as hard rubber, may be used for the body and the teeth structures as well as the adjusting-plugs and the cap, while the valve and its stems, likewise the spring above the valve, may be made of a suitable metal. I find that a metal valve 8 of conical shape and without being faced with soft material operates with satisfaction, and this is one form that I have used.

Having thus described my invention, what I claim, and desire to secure by Letters Patent, is—

30 1. A fountain-comb consisting in the combination of a suitable body provided with a chamber serving as a reservoir, a set of tubular teeth 6 projecting from said body and having their interiors in direct and practically-unobstructed communication with said reservoir to readily receive the liquid therefrom and having their outer ends open for discharging the liquid therefrom, each of said teeth 6 being provided upon its interior near 35 its outer end with a valve-seat 7, a valve 8 closing on said valve-seat whereby substantially the entire interior of the tooth is normally filled with liquid from the reservoir, said

valve being provided with an outer stem 9 which projects through the opening in the end 45 of the tooth and also an inner stem 11 which extends through the bore of the tooth and into the reservoir to lead the liquid therefrom, and a spiral spring 13 surrounding the inner stem of the valve and bearing with one 50 end against the valve 8, and with the other end against a fixed part, the said valve being normally closed on its seat by the spring and adapted to be opened by pressing the outer stem of the valve inwardly into its 55 tooth, substantially as and for the purpose set forth.

2. A fountain-comb consisting in the combination of a suitable body provided with a chamber serving as a reservoir, a set of tubular teeth projecting from said body and in communication with said reservoir and having their outer ends open to discharge the liquid therefrom, each of said teeth being provided upon its interior near its outer end 60 with a valve-seat, a valve provided with an outer stem which projects out of the end of the tooth and also an inner stem which extends through the bore of the tooth thence through the reservoir the wall of which at a 65 point opposite the tooth is provided with a perforation, a removable plug fitting in said perforation and having its inner end formed with a recess for receiving and guiding the end of the inner stem of the valve, and a 70 spring for normally holding the said valve closed, the said spring engaging the said plug, substantially as and for the purpose set forth.

In testimony whereof I have hereunto set 80 my hand in the presence of the two subscribing witnesses.

JULIAN R. HARRISON.
